Specification for Design.

Patented Jan. 23, 1917.

Application filed May 27, 1916. Serial No. 100,430. Term of patent 7 years.

To all whom it may concern:

Be it known that I, MAURICE A. SMITH, a citizen of the United States, and residing at Jeannette, in the county of Westmoreland, State of Pennsylvania, have invented a new, original, and ornamental Design for a Glass Article, of which the following is a specification, reference being had to the accompanying drawing, forming part thereof.

The figure is a view showing my new de-

sign applied to a glass article, the shape of which is not novel and is not herein claimed.

I claim:

The ornamental design for a glass article of manufacture, as shown.

MAURICE A. SMITH.
